UNITED STATES PATENT OFFICE.

ALEXANDER LUETHI, OF LAKEMILLS, WISCONSIN, ASSIGNOR OF TWO-THIRDS TO WILLIAM A. ENGSBERG AND CONRAD ENGSBERG, OF LAKEMILLS, WISCONSIN.

SAD-IRON.

SPECIFICATION forming part of Letters Patent No. 693,876, dated February 25, 1902.

Application filed January 31, 1901. Serial No. 45,429. (No model.)

To all whom it may concern:

Be it known that I, ALEXANDER LUETHI, residing at Lakemills, in the county of Jefferson and State of Wisconsin, have invented a new and useful Improvement in Sad-Irons, of which the following is a description, reference being had to the accompanying drawings, which are a part of this specification.

My invention has relation to improvements in sad-irons of the particular form of construction in which the handle portion is removable.

It is the primary object of my invention to provide an improved construction of the type of sad-iron wherein the handle portion is slidably fitted to the body portion which shall be simple in construction and inexpensive of production.

A still further object resides in an improved construction whereby the catch which is employed for detachably locking the handle portion to the body portion is prevented from accidentally becoming unlocked when the iron is lifted up and turned from its normal horizontal position.

With the above and other incidental objects in view the invention consists of the devices and parts or their equivalents, as hereinafter set forth.

In the accompanying drawings, Figure 1 is a side elevation with parts broken away. Fig. 2 is a sectional view on the line 22 of Fig. 1. Fig. 3 is a rear elevation. Fig. 4 is a plan view of the base of the handle portion, the hand-guard and legs of the handle being removed. Fig. 5 is a section on the line 55 of Fig. 1 looking toward the left, and Fig. 6 is a view of a modified form of hand-guard.

Referring to the drawings, the numeral 7 indicates the body of the iron, which is provided in its top surface with a longitudinal mortise 8, extending from the rear edge of the body forwardly, but terminating short of the forward end of the body. This mortise gradually narrows toward its forward end, and the forward end wall thereof is inclined or beveled, as clearly shown in Fig. 1. The side walls of the mortise, except at the rear end thereof, are vertical, as clearly shown in Fig. 5, while said rear end is of dovetail form

or flared outwardly, as indicated by the numeral 9, the sides of the flaring portion being undercut or beveled.

The removable handle portion of the iron consists of a base 10, a handpiece 11, preferably of wood or some other poor conductor of heat, and a suitable connection between the base and the handpiece. The base is of corresponding shape to and its side walls fit the sides of the longitudinal mortise 8 of the body—that is to say, it has the vertical side walls, which are adapted to fit loosely the corresponding walls of the mortise, and it is provided with the rear flaring or dovetail portion 12, with beveled side walls, which closely fit the corresponding undercut walls of the dovetail portion of the mortise 8. The forward extremity of the base is beveled downwardly to form a projecting tongue 13, which closely fits the correspondingly-beveled end wall of the mortise. The base is also provided at an intermediate point with a slot 14, adapted to accommodate a catch 15. The catch is pivoted on a pin 16, the ends of said pin being mounted in lugs 1717, which extend upwardly from the base. This catch is composed of an upper horizontal or approximately horizontal arm and a lower rearwardly-extending arm, forming practically a bell-crank lever. The pivotal point of the catch is at the angle 80 of these two arms, and said arms therefore extend rearwardly from the pivotal point, so that the weight is on one side of the pivot. For conveniently operating the catch the upper arm thereof is advisably formed with a 85 knob or finger-piece 18. The lower arm of the catch when the base is adjusted to the mortise, as shown in Fig. 1, fits in a depression 19 in the bottom of said mortise, the end of said lower arm preferably bearing against an 90 inclined end wall of the depression.

In the form of construction illustrated in Figs. 1 to 5, inclusive, the connection between the base 10 and the handpiece 11 of the handle portion of the iron is made from a single 95 piece of metal, said metal being bent to form the legs 2020 and the horizontal plate 21, said plate forming a hand-guard. The legs are connected at their upper ends to the opposite ends of the handpiece and are also preferably 100

pressed outwardly longitudinally, as indicated by the numerals 22 22, in order to give strength thereto. The guard-plate is held a slight distance above the base by means of 5 short lugs 23 23, extending upwardly from said base, the plate being connected thereto by means of screws 24 24. The plate is advisably of a width equal to or substantially equal to the width of the body of the iron, so 10 that the hand of the operator grasping the handpiece 11 will be protected from the heat arising from the iron. The said guard-plate, furthermore, is provided with a slot 25 for the accommodation of the upper arm of the catch. 15 It frequently becomes necessary in the use of an iron to lift the same from the ironing-board and tilt the iron slightly in order to test the bottom of the iron and see if it is sufficiently heated. When so lifted and tilted, 20 if no means were provided to guard against such a contingency there would be a tendency of the catch 15 to become disengaged, and consequently the base of the handle portion to become accidentally separated from the 25 body of the iron. To prevent this, I provide a spring-tongue 26, which is adapted to engage a shoulder 27, formed on the catch, which engagement of course causes the catch 15 to remain in engagement with the end wall of 30 the depression 19 under such conditions. The spring-tongue is preferably formed in the guard-plate 21 by providing said plate with elongated slits 28 28, extending to the slot 25 and forming therebetween a springy or elastic tongue. 35

In adjusting the handle portion to the body of the iron the narrow end of the base of the handle portion is first inserted in the rear wide dovetail portion of the mortise and said 40 base slid along until the lower arm of the catch 15 drops into the depression 19. When this engagement occurs, the projecting tongue 13 of the base is seated beneath the inclined forward end of the mortise, and hence the 45 forward end of the base is locked against being withdrawn upwardly out of the mortise. In order to release the handle portion from the body of the iron, all that is necessary to be done is simply to pull upwardly on the 50 knob 18, and this will raise the end of the lower arm of the catch out of engagement with the end wall of the depression 19. The base is then free to be slid rearwardly, and when slid sufficiently far to release the tongue 55 13 the base can then be lifted upwardly out of the mortise. When the two parts are connected in the manner explained, the rear end of the base is in firm engagement with the rear end of the mortise, owing to the dovetail 60 and beveled shape of the rear end of said base, which effects a wedging engagement with the correspondingly-shaped portion of the mortise, and also the tongue 13 closely fits the beveled end wall of the mortise. In view of 65 the fact, however, that the side walls of the remaining portion of the base are vertical and

loosely fit the corresponding walls of the mortise it will be evident that if the metal swells through excessive heat the base can still be readily removed, as it is only necessary to 70 slide the base rearwardly a slight distance to effect this result.

By the employment of the guard-plate 21 the hand of the operator grasping the handpiece 11 is thoroughly protected from the heat 75 which may ascend from the iron. By forming this guard-plate and the legs of the handle portion in one piece simplicity in manufacture is also secured.

In Fig. 6 of the drawings I have shown a 80 guard-plate which is intended to be entirely separate from the legs of the handle and to be employed in connection with a sad-iron of a form of construction in which the legs extend upwardly directly from the base 10—such, for 85 instance, as in the form of sad-iron covered in United States Letters Patent issued to L. Passmore, No. 196,763, dated November 6, 1877. In this modified form the guard-plate is indicated by the numeral 21', said plate being provided with a slot 25' for the accommodation of the catch and with a spring-tongue 26' to engage a shoulder on the catch, as in the principal form of construction. This plate, however, is provided at opposite ends with 90 the slots 29 29, which slots are open at their outer ends. In the form of iron in connection with which this plate is adapted to be used the plate is first adjusted between the legs, so that the legs engage the slots 29, and 95 said plate then adjusted downwardly until it contacts with lugs similar to 23, being secured to said lugs by means of screws or equivalent means.

What I claim as my invention is—

In a sad-iron, the combination of a body portion having a longitudinal mortise in its upper side, said mortise being open at its rear end, a base fitting the mortise of the body, said base provided at an intermediate point 110 with a slot, a plate above and secured to the base and provided with a slot registering with the slot of the base, and also provided with two slits forming a spring-tongue therebetween, and a pivoted catch disposed in the 115 registering slots of the plate and base, and having its lower arm releasably engaging the body, and its upper arm extending above the plate, and one of its edges provided with a shoulder which is adapted to be engaged by 120 the spring-tongue, whereby the lower arm of the catch is held in locked engagement with the body in order to prevent, when the iron is uplifted and tilted, the sliding disengagement of the base from the body of the iron. 125

In testimony whereof I affix my signature in presence of two witnesses.

ALEXANDER LUETHI.
